United States Patent Office

Des. 185,608
Patented June 30, 1959

185,608

STEERING WHEEL BASE

Thomas P. Mainzinger, Grand Rapids, Mich., assignor to
Attwood Brass Works, Inc., Grand Rapids, Mich., a
corporation of Michigan

Application May 14, 1958, Serial No. 50,881

Term of patent 14 years

(Cl. D71—1)

Fig. 1

Fig. 2

Fig. 3

Fig. 1 is a perspective view of a steering wheel base, showing my new design.

Fig. 2 is a side elevation view thereof.

Fig. 3 is a front elevation view thereof.

I claim:

The ornamental design for a steering wheel base, as shown.
